WINDSHIELD SCREEN

Filed-Sept. 9, 1926

UNITED STATES PATENT OFFICE

EDGAR B. CLEMENT AND RAYMOND J. THOMPSON, OF JACKSON, MICHIGAN

WINDSHIELD SCREEN

Application filed September 9, 1926. Serial No. 134,504.

The main object of this invention is to provide a screened windshield of the ventilator type in which the screen does not interfere with the opening and closing of the 5 windshield pane and protects the opening both when adjusted to fully open the pane or when it is opened to provide a ventilating opening only.

A further object is to provide a screen 10 which may be readily attached to windshields of the ventilator type.

Objects pertaining to details and economies of our improvements will definitely appear from the detailed description to follow. The invention is clearly defined and pointed out in the claims.

A structure embodying the features of our invention is clearly illustrated in the accompanying drawing forming a part of 20 this application, in which:

Fig. 1 is a fragmentary perspective view of a vehicle body having a ventilating windshield equipped with our invention.

Fig. 2 is a fragmentary rear elevation of 25 the screen proper.

Fig. 3 is a fragmentary perspective view showing the manner of attaching the screen.

Fig. 4 is a fragmentary vertical section on a line corresponding to line 4-4 of Fig. 30 1 showing further details in the arrangement and attachment of the screen.

Fig. 5 is a detail horizontal section illustrating a modified form of attaching means.

Fig. 6 is a fragmentary section illustrating still another form of attaching means.

Fig. 7 is a fragmentary vertical section showing a modified form of screen support.

Referring to the drawing, 1 represents 40 the vehicle body which is shown conventionally. The body is provided with a windshield frame comprising a sill member 2 having a forwardly facing gutter 3 therein, the sill member being inclined forwardly from this gutter. The frame has vertical 45 ways 4 in which the pane 5 is mounted for vertical sliding movement. These ways are formed by suitable stops the arrangement of which forms no part of this invention. It should be noted, however, that the pane 50 closes in front of the gutter.

At the rear of the sill is an air deflector or ventilator 6 having its upper edge 7 curved forwardly and overhanging the sill member but spaced from the pane. We provide a screen 8 having a bottom frame member 9 55 preferably offset rearwardly to engage in the gutter 3. The screen is provided with a top frame designated generally by the numeral 10 carrying a resilient facing 11 bearing against the inner side of the pane and 60 with which the pane slidably engages.

At its ends the screen is provided with frame pieces 12 having angled plates 13 adapted to overlie the window stop 14 and rest against the outer side of the finishing 65 strip 15. The attaching plates have slots 16 therein positioned to receive one of the attaching screws 17 of the strip 15.

The screen is preferably provided with a vertical cross piece 18 for reinforcing and 70 stiffening the same, this cross piece having a downwardly projecting supporting finger 19 engaging the deflector 6 as shown in Fig. 4. With the parts thus arranged the screen may be quickly attached or detached and is 75 supported so that it is free from vibration and rattling, and so that it is effective in screening the opening to the ventilator and also when the windshield pane is fully raised.

In the modification shown in Fig. 5 the attaching plates 20 are conformed to fit under the finishing strip 15 and to be clamped thereby.

In the modification shown in Fig. 6 the 85 attaching plate 21 is provided with a flange 22 adapted to be clamped by the edge of the finishing strip 15, the attaching plate overlying the strip.

In Fig. 7 the screen is provided with a 90 clip-like attaching member 23 slotted at 24 to receive the edge of the deflector 7 to which it is secured by means of the set screw 25.

We have not attempted to illustrate or 95 describe certain other embodiments or adaptations which we contemplate as we believe the disclosure made will enable those skilled in the art to embody or adapt our improvements as may be desired.

Having thus described our invention what 100

we claim as new and desire to secure by Letters Patent is:

1. The combination with a windshield frame provided with a sill member having a forwardly facing gutter therein, a vertically slidable windshield pane closing in front of said gutter, a screen provided with a rearwardly offset bead-like bottom member engaging said gutter and with a top member having a facing strip engaging the inner side of the pane and with end members having rearwardly projecting attaching plates secured to the side members of said windshield frame, an air deflector disposed at the rear of and in spaced relation to the sill member, a vertical cross piece connecting the top and bottom members of said screen, and a supporting finger on said cross piece engaging said deflector. 70
2. The combination with a windshield frame provided with a sill member having a forwardly facing gutter therein, a vertically slidable windshield pane closing in front of said gutter, a screen provided with a rearwardly offset bead-like bottom member engaging said gutter and with a top member having a facing strip engaging the inner side of the pane and with end members having rearwardly projecting attaching plates secured to the side members of said windshield frame, and an air deflector disposed at the rear of and in spaced relation to the sill member. 75
3. The combination with a windshield frame provided with vertical slideways for the windshield pane and with a bottom sill having a forwardly facing gutter disposed at the rear of said slideways, a windshield pane, a deflector disposed at the rear of said sill member with its upper edge overhanging the same and in spaced relation to the windshield pane, a screen disposed between said deflector and windshield pane with its lower edge in front of said gutter and its upper edge on the inside of the pane, attaching plates on the ends of said screen, and a member intermediate the ends of said screen for attaching it to said deflector. 80
4. The combination with a windshield frame provided with vertical slideways for the windshield pane and with a bottom sill having a forwardly facing gutter disposed at the rear of said slideways, a windshield pane, a screen disposed with its lower edge in front of said gutter and its upper edge on the inside of the pane, and attaching plates on the ends of said screen. 85
5. The combination with a windshield frame provided with vertical slideways for the windshield pane and with a bottom sill having a forwardly facing gutter disposed at the rear of said slideways, a windshield pane, a screen disposed with its lower edge in front of said gutter and its upper edge on the inside of the pane and provided with a facing with which said pane slidably engages, and attaching plates on the ends of said screen. 90
6. The combination in a vehicle body, of a windshield frame having vertical slideways and a sill member provided with a forwardly facing gutter, an air deflector spaced from and overhanging said bottom member, a screen provided with a frame comprising top, bottom and end members, the bottom member being engaged in said gutter, the top member being provided with a resilient facing engaging the rear side of the windshield, and the end members being provided with rearwardly projecting attaching plates disposed against the side of the side members of the frame, a cross piece connecting said top and bottom screen members, and a supporting member on said cross piece engaging the said deflector. 95
7. The combination in a vehicle body of a windshield frame having vertical slideways and a sill member provided with a forwardly facing gutter, an air deflector spaced from and overhanging said bottom member, and a screen provided with a frame comprising top, bottom and end members, the bottom member being engaged in said gutter, the top member being provided with a resilient facing engaging the rear side of the windshield, and the end members being provided with rearwardly projecting attaching plates disposed against the side of the side members of the frame. 100
8. The combination with a windshield frame provided with a sill member having a forwardly facing gutter therein, a vertically slidable windshield pane closing in front of said gutter, a screen disposed with its lower edge in front of the gutter and its upper edge at the rear of the pane, and an air deflector disposed at the rear of said screen. 105
9. The combination with a windshield frame provided with a sill member having a forwardly facing gutter therein, a vertically slidable windshield pane closing in front of said gutter, and a screen disposed with its lower edge in front of the gutter and its upper edge at the rear of the pane. 110
10. The combination in a vehicle body of a windshield frame having vertical slideways and having a windshield pane slideable in said slide ways, a sill member provided with an upstanding gutter part, an air deflector spaced from and overhanging said sill member, and a screen disposed between said deflector and pane with its lower edge in supporting engagement with said gutter part and its upper edge at the rear of the pane. 115
11. The combination with a windshield frame provided with vertical slideways for a windshield pane and with a sill member, a windshield pane, a deflector disposed at 120
- 125
- 130

the rear of and overhanging said sill member, and a screen disposed between said windshield pane and said deflector with its upper edge at the rear of the pane and its lower edge in supporting engagement with
5 said sill whereby the pane opening is completely screened above and below the said deflector.

In witness whereof we have hereunto set
our hands.
